(57) **CLAIM**

The ornamental design for a terminal fitting for electric connector as shown and described.

DESCRIPTION

FIG. 1 is a front, top and right-side perspective view of a first embodiment of a terminal fitting for electric connector showing our new design;

FIG. 2 is a rear, bottom and left-side perspective view thereof;

FIG. 3 is a front elevational view thereof;

FIG. 4 is rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a cross-sectional view taken along line 9-9 in FIG. 5;

FIG. 10 is a front, top and right-side perspective view of a second embodiment of a terminal fitting for electric connector showing our new design;

FIG. 11 is a rear, bottom and left-side perspective view thereof;

FIG. 12 is a front elevational view thereof;

FIG. 13 is rear elevational view thereof;

FIG. 14 is a left-side elevational view thereof;

FIG. 15 is a right-side elevational view thereof;

FIG. 16 is a top plan view thereof;

FIG. 17 is a bottom plan view thereof; and,

FIG. 18 is a cross-sectional view taken along line 18-18 in FIG. 14.
